WELT BEATING MACHINE

James P. Fredericksen, Braintree, Mass., assignor
to United Shoe Machinery Corporation, Flem-
ington, N. J., a corporation of New Jersey

Application April 4, 1944, Serial No. 529,461

12 Claims. (Cl. 12—67.2)

This invention relates to welt beating machines, and is herein illustrated as embodied in a machine of the type disclosed in United States Letters Patent No. 875,171, granted December 31, 1907, upon application filed in the name of J. B. Hadaway, and adapted for beating out welts of lasted shoes.

Welt beating machines of the type aforementioned which have gone into extensive commercial use commonly employ slashing mechanism in the form of a knife, which is used to slash the welt as the machine operates upon the welt along the toe portion of the shoe, the purpose being to cut the material of the welt in order that the welt may be flattened out more readily at the places where it is sharply bent to conform to the curvature of the shoe bottom. It is an object of the present invention to provide an improved welt beating machine, which is adapted to beat out welts along sharply curved portions thereof without the necessity for slashing the welts.

To this end and as shown, the invention provides, in a machine of the type referred to, a work support and an oscillatory hammer for beating out a welt positioned upon the support, the support having a recess therein, and there being an auxiliary hammer arranged progressively to force marginal portions of the welt into the recess. Preferably and as shown, the first-mentioned hammer has portions adapted to engage and to grip portions of the welt upon opposite sides of the recess and hold such portions in fixed position while the hammer is down upon the work, so that the auxiliary hammer will be effective to stretch the welt between the gripped portions. Preferably also, the recess is of increasing depth and width inwardly of the work support, so that the outer portion of the welt is stretched more than the inner portion thereof with the result that it can readily be flattened out into the plane of the shoe bottom.

These and other features of the invention are illustrated in the accompanying drawing, are described in the following specification, and are pointed out in the claims.

In the drawing,

Fig. 1 is a side view of a portion of a welt beating machine embodying my invention;

Fig. 2 is a front elevation of the work support and associated parts of the machine;

Fig. 3 is a perspective view, on an enlarged scale and partly in section, of a portion of the machine illustrating operation upon a shoe; and

Fig. 4 is a view in side elevation on an enlarged

scale showing a shoe in operative relation to the machine.

As shown in Fig. 1, the machine comprises a frame 10 carrying a work support 12 in the form of an anvil arranged to support the welt 14 of a lasted shoe 16, Figs. 3 and 4, to be operated upon, and an oscillating arm 18 carrying a hammer 20 for beating out the welt, there being an auxiliary hammer 22 carried by the arm for progressively stretching marginal portions of the welt by forcing the material of the welt into a recess 24 in the anvil.

The anvil 12 has a shank 26 and a raised portion 28 having a flat horizontal work supporting surface 30 and terminating in a nose portion 32 adapted to enter the welt crease of a shoe to guide it along the support while the welt of the shoe rests upon the supporting surface. The shank 26 is mounted upon a bracket 34 on the frame 10 for adjustment laterally of the hammer and is arranged to be secured in fixed position by a bolt 36 extending through an elongated slot 38 in the bracket and threaded into the shank. As best shown in Figs. 2 and 3, the recess 24 is in the form of a V-shaped notch, which extends inwardly from a point slightly spaced from the end of the nose portion 32 and increases in width and depth in a direction away from the nose portion.

The arm 18 is mounted upon a pivot 40 and is arranged to be oscillated toward and away from the anvil 12 by a power driven eccentric 42. The main hammer 20 is carried by a rod 44 slidably mounted in a boss 46 on the arm 18 and is normally arranged to be forced downwardly by a spring 48, the lower end of which rests upon a shoulder 50 on the rod, and the upper end of which bears against a collar 52 screw-threaded into the upper end of the boss. The downward position of the hammer is limited by a stop nut 54 carried by the reduced upper end of the rod and arranged to engage a washer 56 resting upon the upper end of the collar, thereby to limit downward movement of the hammer under the action of the spring. The lower end of the hammer is slotted, as shown at 58, Figs. 2 and 3, forming two work-engaging portions 60, which are disposed upon opposite sides of the recess 24 in the anvil and operate, upon successive downward movements of the hammer, to beat down the inseam materials and to flatten the welt on the anvil. During each cycle the portions 60 momentarily clamp the welt down upon the anvil. The portions 60 of the striking face of the hammer are serrated, as shown at 62, for the

purpose of firmly gripping the stock when the hammer is down upon the welt to prevent movement of the gripped portions relatively to the anvil.

The auxiliary hammer 22 is in the form of a plate positioned in the slot 58 of the main hammer, and has a laterally extending shank 63 secured rigidly to the arm 18 by bolts 64 extending through elongated slots 66 in the shank and screw-threaded into the arm. The lower end of the auxiliary hammer 22 is rounded transversely and is shaped to converge with the bottom of the central portion of the recess 24 with which it is aligned. Fig. 2 shows the positions of the two hammers when in lowermost position with no work in the machine. Figs. 3 and 4 illustrate how the welt along the toe of a shoe being operated upon is gripped between the main hammer and the anvil with a portion of the welt forced into the recess. As shown in these figures, the downward movement of the hammer 20 has been arrested by engagement with the work and the auxiliary hammer 22 has moved below the hammer 20 forcing portions of the welt into the recess. Preferably, the position of the auxiliary hammer is adjusted so that it will engage the welt at points adjacent the seam of the shoe to be operated on and outwardly to the edge of the welt, so that the welt will be beaten down to close the feather on the welt and at the same time so that the marginal portions of the welt are forced into the recess to stretch the same.

In the operation of the machine, when the arm 18 is oscillated in a direction toward the anvil, the main hammer 20 first engages the welt and inseam materials delivering a blow thereto which tends to flatten them out, and, while the hammer is down on the work and under the pressure of the spring 48, the auxiliary hammer 22 forces the material of the welt between the portions gripped by the main hammer into the recess to stretch the welt. As the shoe is advanced along the anvil, successive operations of the hammers serve progressively to stretch out small marginal portions of the welt, and then to flatten them. Since the face of the auxiliary hammer converges with the bottom of the recess inwardly of the nose portion of the anvil, progressively greater pressure is applied to the welt outwardly of the seam where more stretching is required. Furthermore, since the outwardly disposed portions of the welt are forced into the deeper part of the recess 24, such portions are stretched more than those portions which lie closer to the seam of the shoe. The result of this is to stretch the welt so that it will conform closely to the shape of the shoe bottom, and the beating action of the main hammer progressively applied along the stretched portions of the welt results in flattening it until it lies substantially in the plane of the shoe bottom.

The pounding of the auxiliary hammer upon the material along the seam tends to remove irregularities in the seam, as well as closing the feather in the welt, thus contributing to the appearance of the finished shoe.

Having described my invention, what I claim as new and desire to secure by Letters Patent of the United States is:

1. A machine for operating upon shoes comprising, a work support, a hammer mounted for oscillation relatively to the support for beating the welt of a shoe, the work support having a recess therein, and an auxiliary hammer mounted for movement relatively to the first-mentioned

hammer for progressively forcing the material of the welt into the recess.

2. A machine for operating upon shoes comprising a work support, a hammer mounted for oscillation relatively to the work support for beating the welt of a shoe, the work support having a recess, projections on the hammer arranged to engage the welt upon opposite sides of the recess to press it against the work support during operation of the hammer, and a second hammer mounted for movement relatively to the first-mentioned hammer for engaging material positioned upon the anvil over the recess to force the same into the recess thereby to stretch it.

15 3. A machine for operating upon shoes comprising an anvil having an upwardly disposed work supporting surface and a recess in the surface, a hammer mounted for oscillation relatively to the anvil and having portions for engaging the work upon opposite sides of the recess, and a second hammer mounted for oscillation with the first-mentioned hammer and located between said portions for engaging the work thereby to stretch it.

20 4. A welt beating machine comprising an anvil having an upwardly disposed work supporting surface terminating in a nose portion adapted to enter the welt crease of a shoe to be operated upon, a V-shaped recess in the work supporting surface of the anvil, the recess being of increasing depth and width in a direction away from the nose portion, an oscillating arm, a hammer yieldably mounted in the arm for engaging portions of the welt of the shoe positioned upon the anvil, and an auxiliary hammer fixedly secured to the arm for forcing marginal portions of the welt into the recess to stretch the same while the first-mentioned hammer is down upon the work.

25 5. A welt beating machine comprising an oscillatory arm, a hammer yieldably mounted upon the arm, the hammer having a slot therein extending heightwise thereof, an auxiliary hammer extending into the slot and fixedly secured to the arm, and an anvil having a work supporting surface extending adjacent to the first-mentioned hammer and having a recess therein in alignment with the auxiliary hammer, the first-mentioned hammer having portions for gripping the work to be operated upon on opposite sides of the recess and the auxiliary hammer having a work engaging portion for forcing into the recess material between the portions gripped by the first-mentioned hammer.

30 6. A welt beating machine comprising an anvil having an upwardly disposed work supporting surface, a recess in the surface, an arm arranged for oscillation toward and away from the work supporting surface, a hammer yieldably mounted in the arm and having work engaging portions extending on opposite sides of the recess, and an auxiliary hammer mounted upon the arm and extending in alignment with the recess for forcing portions of the work being operated upon into the recess.

35 7. A welt beating machine comprising an anvil having a work supporting surface, a recess in the surface, an arm mounted for oscillation toward and away from the anvil, a hammer yieldably mounted in the arm for engaging work positioned upon the anvil, the hammer having a slot extending heightwise thereof and in alignment with the recess, and an auxiliary hammer fixedly secured to the arm and located in the slot.

40 8. A welt beating machine comprising an anvil

having a work supporting surface, a recess in the surface, an arm mounted for oscillation toward and away from the anvil, a hammer yieldably mounted in the arm for engaging work positioned upon the anvil, the hammer having a slot extending heightwise thereof and in alignment with the recess, and an auxiliary hammer fixedly secured to the arm and located in the slot, the auxiliary hammer having a work engaging portion extending at an inclination to the work supporting surface.

9. A welt beating machine comprising an anvil having a work supporting surface, a recess in the surface, an arm mounted for oscillation toward and away from the anvil, a hammer yieldably mounted in the arm for engaging work positioned upon the anvil, the hammer having a slot extending heightwise thereof and in alignment with the recess, an auxiliary hammer fixedly secured to the arm and located in the slot, and means mounting the auxiliary hammer for adjustment laterally of the first-mentioned hammer.

10. A welt beating machine comprising an anvil, an arm arranged for oscillation toward and away from the anvil, the anvil having a recess therein, a hammer yieldably mounted in the arm

and having work engaging portions extending upon opposite sides of the recess, and an auxiliary hammer fixedly secured to the arm and having a work engaging portion in alignment with the recess and converging with the bottom of the recess.

11. A welt beating machine comprising an anvil, an arm mounted for movement toward and away from the anvil, a hammer yieldably mounted upon the arm, a recess in the anvil, said hammer having work engaging portions extending upon opposite sides of the recess, and an auxiliary hammer fixedly secured to the arm and positioned between said portions in alignment with the recess.

12. A welt beating machine comprising an anvil, an arm mounted for movement toward and away from the anvil, a hammer yieldably mounted upon the arm, a recess in the anvil, said hammer having work engaging portions extending upon opposite sides of the recess, the work engaging portions having serrations, and an auxiliary hammer fixedly secured to the arm and positioned between said portions in alignment with the recess.
